UNITED STATES PATENT OFFICE.

THURE DAHL, OF BROOKLYN, NEW YORK, ASSIGNOR TO LIGHTOLIER COMPANY, OF NEW YORK, N. Y., A CORPORATION OF NEW YORK.

DESIGN FOR A COMBINATION HOOK AND SOCKET COVER LIGHTING-FIXTURE.

53,005.

Specification for Design.

Patented Feb. 18, 1919.

Application filed October 31, 1918. Serial No. 260,615. Term of patent 7 years.

To all whom it may concern:

Be it known that I, THURE DAHL, residing and having my post-office address at #328 73d street, borough of Brooklyn, county of Kings, State of New York, and a subject of the King of Sweden, have invented a new, original, and ornamental Design for a Combination Hook and Socket Cover Lighting-Fixture, of which the following is a specification, reference being had to the accompanying drawing, forming part thereof.

The figures show a plan view of the front

and two sides of a combination hook and socket cover lighting fixture, showing my new design.

I claim:

The ornamental design for a combination hook and socket cover lighting fixture as shown.

THURE DAHL.
